[57] CLAIM

The ornamental design for a lavatory, as shown and described.

DESCRIPTION

FIG. 1 is a left side elevational view of a wall-mountable lavatory embodying my new design, the right side elevational view being a mirror image of the left side shown; FIG. 2 is a front elevational view thereof;

FIG. 3 is a top plan view thereof;

FIG. 4 is a cross-sectional view taken along line 4—4 of FIG. 2;

FIG. 5 is a left side elevational view of a second embodiment in the form of a pedestal lavatory, the right side elevational view being a mirror image of the left side shown, and the top plan view thereof being identical to that shown in FIG. 3; FIG. 6 is a front elevational view thereof; and, FIG. 7 is a cross-sectional view taken along line 7—7 of FIG. 6.

The broken line representations of holes in FIG. 3 are for purposes of illustration only, and form no part of the claimed design.
